(57) **CLAIM**

The ornamental design for a tire for automobile, as shown and described.

DESCRIPTION

FIG. 1 is a perspective view of an tire for automobile showing the new design;

FIG. 2 is a front view of the tire for automobile in FIG. 1, it being understood that the pattern repeats uniformly throughout the circumference of the tire;

FIG. 3 is a rear view of the tire for automobile shown in FIG. 1; and,

FIG. 4 is a left side view of the automobile tire shown in FIG. 1, which is the same as the right side view thereof.
